LIGHTING FIXTURE

Albert Gamerdinger, Glenside, Pa.

Application September 9, 1954, Serial No. 32,207

Term of patent 7 years

(Cl. D48—4)

FIG. 1

FIG. 2

FIG. 3

To all whom it may concern:

Be it known that I, Albert Gamerdinger, a citizen of the United States and resident of Glenside, State of Pennsylvania, U. S. A., have invented a new, original, and ornamental Design for a Lighting Fixture, of which the following is a specification, reference being made to the accompanying drawing, forming a part thereof.

In the drawing:

Figure 1 is a perspective view of a lighting fixture, showing my new design;

Figure 2 is a front elevational view, on a reduced scale, of the lighting fixture; and

Figure 3 is a side elevational view, on a reduced scale, of the lighting fixture.

I claim:

The ornamental design for a lighting fixture, substantially as shown.
